UNITED STATES PATENT OFFICE.

JOSEPH L. FIRM, OF BERWYN, ILLINOIS, ASSIGNOR TO THE GOSS PRINTING PRESS COMPANY, OF CHICAGO, ILLINOIS, A CORPORATION OF ILLINOIS.

WEB-PERFECTING PRESS.

1,178,907.

Specification of Letters Patent. Patented Apr. 11, 1916.

Application filed May 7, 1915. Serial No. 26,497.

To all whom it may concern:

Be it known that I, JOSEPH L. FIRM, a citizen of the United States, residing at Berwyn, in the county of Cook, State of Illinois, have invented certain new and useful Improvements in Web-Perfecting Presses, of which the following is a specification, reference being had to the accompanying drawings.

10 My invention relates to web-perfecting presses and particularly to that type of press which is adapted to be used for printing in colors either by the use of printing plates of the ordinary type adapted to impress the 15 colors directly from the plates upon the web or by the use of lithographic plates which deposit the ink upon transfer cylinders for subsequent impression upon the web.

It is one of the principal objects of my 20 invention to provide a new and improved arrangement and organization of parts by which there shall be a greater range in the operation of a machine of this type and a consequent greater range in the products 25 capable of being produced, and by which the change from one mode of operation to another may be readily and quickly made.

It is another object of my invention to 30 provide an improved combination of parts comprising efficient means for cleaning the ink from the transfer cylinder and for keeping the transfer cylinder clean during the operation of the machine.

It is another object of my invention to 35 improve web-perfecting presses of the general type set forth in sundry details hereinafter set forth.

The preferred means by which I have accomplished my several objects are illustrated in the drawings and are hereinafter 40 specifically described.

That which I believe to be new and desire to cover by this application is set forth in the claims.

45 In the drawings, Figure 1 is a side view showing diagrammatically the arrangement of the operative parts of the printing portion of my improved press; Fig. 2 is an enlarged detail, being a transverse vertical section 50 through one of the cylinders forming a part of my improved cylinder-cleaning mechanism, being a section taken substantially on line 2—2 of Fig. 3; and Fig. 3 is a side view of the parts shown in Fig. 2, being partly

broken away, and being partly in section as 55 seen upon the line 3—3 of Fig. 2.

Referring to the several figures of the drawings, in which corresponding parts are indicated by the same reference characters,— 60 10 indicates a combination transfer and impression cylinder. An impression cylinder 11 is adapted to be revolved in contact with the cylinder 10. Plate-cylinders 12—13 are adapted to be revolved in contact with the cylinder 10, in the construction shown each 65 of the plate-cylinders 12—13 being provided with two plates 14 comprising lithographic plates of any suitable construction.

Adjacent to each of the plate-cylinders 12—13 is a water mechanism 15 adapted to 70 apply a thin film of water to lithographic plates carried by said cylinders, or adapted to be moved back out of operative position, or to be otherwise thrown out of operation, when stereotype plates or other printing 75 plates of the ordinary type are employed, the term "printing plates" being used throughout the specification and claims to designate a distinctly relief printing plate as distinguished from a lithographic plate. 80

Adjacent to the plate-cylinders 12—13 are inking-mechanisms 16—17, respectively, adapted to apply ink to the plates carried by the said plate-cylinders. The inking-mechanism 16 comprises two ink-fountains 18—19, 85 together with means of the ordinary type for transferring ink from the fountain for distribution, and the inking-mechanism 17 is likewise provided with two fountains 20—21. The plate-cylinders 12—13 are adapted to 90 be rotated in either direction as hereinafter described. As will be readily understood, when the plate-cylinders are rotated in counterclockwise direction as indicated by the arrows in Fig. 1, the ink-fountains 19 and 95 20 will be employed; when the plate-cylinders are revolved in the opposite direction, the ink-fountains 18 and 21 will be employed.

Means is provided for cleaning the surface 100 plus ink from the transfer-cylinder 10 when the cylinder 10 is used as a transfer-cylinder, the cleaning mechanism being adapted to be removed from operative position when the cylinder 10 is being used as an impression cylinder. The cleaning mechanism comprises composition-rollers 22—23 adapted 105 to contact the rubber surface of the trans-

fer cylinder 10. A cylinder 24, preferably having a face of iron, is rotatable in contact with the composition-cylinders 22-23. As transfer cylinder 10 rotates in clockwise direction in Fig. 1 with the plate-cylinders 12-13 provided with lithographic plates, the ink is transferred from the lithographic plates to the transfer cylinder 10, the greater part of such ink being transferred 5 in turn from the cylinder 10 to a web 25 passing from a roll 26 about the impression cylinder 11. The surplus ink is then transferred from the rubber surface of the transfer cylinder 10 to the composition-rollers 15 23-22 and from such composition-rollers to the iron surface of the cylinder 24. Means is provided for cleaning the surface of the cylinder 24 comprising a tank 27 provided with means in contact with which 20 the cylinder 24 is adapted to be rotated. The tank 27 is adapted to be moved upward relative to the cylinder 24 so as to bring the cleaning means into proper engagement with the cylinder. Whenever desired, the tank 27 may be lowered out of 25 contact with the cylinder and drawn out from under the cylinder into position upon a table 28 suitably supported upon the framework 29, in which position the cleaning 30 means can be adjusted as desired. The tank 27 is provided with plates 30-31 dividing it longitudinally into three compartments, in each of which is placed a bag 32 formed of mole-skin cloth filled with cut 35 sponges, or other suitable absorbent material. The tank 27 is adapted to be filled with water containing a heavy solution of pearlash, or other suitable detergent. At the side of the tank 27 toward which the 40 lower portion of the cylinder 24 moves in the rotation of the cylinder in clockwise direction in Fig. 2, is inserted a plate or block 33 of rubber or other suitable material. The block 33 is adapted to be pressed inward 45 into contact with the cylinder 24 by means of a series of screws 34 which are mounted in the side of the tank 27 and engage at their inner ends a steel plate or plates 35 against which the rubber block 34 lies. The 50 tank 27 is adapted to be moved upward to bring the bags 32 into proper engagement with the cylinder 24 by means of screws 36-37 which are loosely journaled in cross-bars 38-39, respectively, secured in any 55 suitable manner to the framework 29. Mounted by means of screw-threads upon the upper ends of the screws 36-37 is a plate 40 upon which the tank 27 rests. The lower ends of the screws 36-37 are provided 60 with bevel-gears 41-42, respectively, meshing with bevel-gears 43-44 which are mounted upon a longitudinally-extending shaft 45 carried by cross-bars 46-47 suitably supported from the framework 29. A 65 crank 48 is mounted upon one end of the

shaft 45 for rotating the said shaft for driving the screws 36-37 for raising and lowering the plate 40 and with it the tank 27. As will be readily understood, when the plate 40 is lowered to its lowermost position, the edges of the tank 27 are brought to rest upon flanges 49-50 of the framework, upon which flanges the tank may be drawn longitudinally into position upon the table 28.

Additional means is provided comprising two combination transfer and impression cylinders 51-52 adapted to be revolved in contact with each other. Plate-cylinders 53-54 are adapted to be revolved in contact with the cylinders 51-52, respectively, each of such plate-cylinders being provided with two plates 55 comprising operative faces in the form of lithographic plates, or printing plates, as may be desired. Inking-mechanisms 56-57 are provided for inking the plates upon the cylinders 53-54, respectively. The inking-mechanism 56 comprises two inking-fountains 58-59, and the inking-mechanism 57 comprises two ink-fountains 60-61. The plate-cylinders 53-54 are adapted to be rotated in either direction as hereinafter described. When the plates are rotated in the direction indicated by the arrows in Fig. 1, the ink-fountains 58 and 60 will be employed, together with means for transferring the ink from such fountains; when the plate-cylinders 53-54 are rotated in the opposite directions, the ink-fountains 59 and 61 will be employed with their transferring mechanisms.

Two water mechanisms 62-63 are provided in connection with the plate-cylinder 54, either or both of which can be moved back out of engagement with the plates upon such cylinder, or otherwise thrown out of operation. As will be readily understood, when the plate-cylinder 54 is rotated in counterclockwise direction as indicated by the arrow in Fig. 1, when lithographic plates are mounted upon said plate-cylinder, the water mechanism 62 will be employed for moistening such lithographic plates in advance of the inking of such plates by the inking-mechanism 57. When the plate-cylinder 54 rotates in the opposite direction, the water mechanism 63 will be employed, provided lithographic plates are being used. When relief printing plates are being employed upon the cylinder 54, neither one of the water mechanisms 62-63 is designed to be used.

With the plate-cylinders 12 and 13 provided with lithographic plates and with the plate-cylinders 53-54 provided with printing plates, and with the various parts being rotated by any suitable means in the directions indicated by the arrows, the web from the roll 26 will be passed about the impres-

70

sion cylinder 11 and thence between the transfer cylinders 51—52 as indicated in solid lines in Fig. 1. With the fountain 19 filled with a suitable blue ink and the fountain 20 filled with a suitable yellow ink, and with the fountains 18 and 21 thrown out of operation, the web 26 would receive from the transfer cylinder 10 the designs in blue, yellow and green which the lithographic plates were intended to produce. The ink-fountains 59 and 61 being thrown out of operation and the ink-fountains 58 and 60 being provided with black ink, the web would be completed upon both sides by its passage between the combination transfer and impression cylinders 51—52, the transfer cylinder 51 making a complete design on the one side of the paper and the transfer cylinder 52 applying the key impression upon the already partly completed opposite face. If it were desired that the plate-cylinder 54 be provided with lithographic plates rather than printing plates, the water mechanism 62 would be employed for moistening such lithographic plates. Any other color of ink might be employed in the fountain 60 if desired. In such operation of the machine the rollers 22—23 and the cylinder 24 in combination with the devices coöperating therewith serve to keep the transfer cylinder 10 clean during the web-perfected operation. If it were desired, similar cleaning mechanism might be employed in connection with the transfer cylinder 52, as will be readily understood.

In case it were desired to produce a multi-color product by the use of printing plates in lieu of lithographic plates in the manner above described, the various cylinders and inking mechanisms would be rotated in the opposite directions from those indicated by the arrows on Fig. 1. In that case inking-fountains 18, 21, 59 and 61 would be used in lieu of the fountains 19—20, 58 and 60, as above described. The web 25 would be led from the roll 26 about the impression cylinder 10 as indicated in dotted lines in Fig. 1, receiving the impression directly from the printing plates rather than from an interposed transfer cylinder. The composition rollers 22—23 will preferably have been removed so as to permit the web 25 to pass from the impression cylinder 10 to a roller 64 from which the web would pass downward about the impression cylinder 52, between the cylinders 52—51, upward about the impression cylinder 51, and downward under the roller 65, producing thus a perfected web in colors.

What I claim as my invention and desire to secure by Letters Patent, is

1. In a press, the combination of a transfer cylinder, a plate cylinder adapted to revolve in contact therewith, means for applying water to the surface of lithographic

plates carried by said plate cylinder, inking mechanism adapted to ink said plates, and means for cleaning the ink from said transfer cylinder, comprising a cylinder, a receptacle in which said cylinder is rotated, absorbent means located in said receptacle in contact with said cylinder, and means for adjusting said receptacle relative to said cylinder. 70

2. In a press, the combination of a transfer cylinder, a plate cylinder adapted to revolve in contact therewith, means for applying water to the surface of lithographic plates carried by said plate cylinder, inking mechanism adapted to ink said plates, and means for cleaning the ink from said transfer cylinder, comprising two composition rollers adapted to rotate in contact with said transfer cylinder, an iron-surfaced cylinder adapted to rotate in contact with said composition rollers, a receptacle in which said cylinder is rotated, absorbent means located in said receptacle in contact with said cylinder, means for adjusting said receptacle relative to said cylinder, and a squeegee device carried by said receptacle adapted to be pressed firmly against said cylinder. 80

3. In a press, the combination of a transfer cylinder, a plate cylinder adapted to revolve in contact therewith, means for applying water to the surface of lithographic plates carried by said plate cylinder, inking mechanism adapted to ink said plates, and means for cleaning the ink from said transfer cylinder, comprising a cylinder, a receptacle in which said cylinder is rotated, means for adjusting said receptacle relative to said cylinder, and one or more bags of moleskin cloth filled with cut sponges in position in said receptacle adapted to be brought into firm contact with said cylinder. 95

4. In a press, the combination of a transfer cylinder, a plate cylinder adapted to revolve in contact therewith, means for applying water to the surface of lithographic plates carried by said plate cylinder, inking mechanism adapted to ink said plates, and means for cleaning the ink from said transfer cylinder, comprising a cylinder, a receptacle in which said cylinder is rotated, means for adjusting said receptacle relative to said cylinder, an absorbent member located in said receptacle and adapted to be brought into firm contact with said cylinder, and a detergent solution in said receptacle about 100 said absorbent member. 110

5. In a press, the combination of a transfer cylinder, a plate cylinder adapted to revolve in contact therewith, means for applying water to the surface of lithographic plates carried by said plate cylinder, inking mechanism adapted to ink said plates, and means for cleaning the ink from said transfer cylinder, comprising a cylinder, a receptacle in which said cylinder is rotated, means 125

for adjusting said receptacle relative to said cylinder, one or more bags of moleskin cloth filled with cut sponges located in said receptacle and adapted to be brought into firm contact with said cylinder, and a detergent solution in said receptacle about said bags.

6. In a press, the combination of a transfer cylinder, a plate cylinder adapted to revolve in contact therewith, means for applying water to the surface of lithographic plates carried by said plate cylinder, inking mechanism adapted to ink said plates, and means for cleaning the ink from said transfer cylinder, comprising a cylinder, a receptacle in which said cylinder is rotated, means for adjusting said receptacle relative to said cylinder, means for dividing said receptacle into a plurality of compartments, a bag of moleskin cloth filled with cut sponges located in each of said compartments and adapted to be brought into firm contact with said cylinder, and a detergent solution in said receptacle about said bags.

7. In a press, the combination of a transfer cylinder, a plate cylinder adapted to revolve in contact therewith, means for applying water to the surface of lithographic plates carried by said plate cylinder, inking mechanism adapted to ink said plates, and means for cleaning the ink from said transfer cylinder, comprising a cylinder, a receptacle in which said cylinder is rotated, means for adjusting said receptacle relative to said cylinder, an absorbent member located in said receptacle and adapted to be brought into firm contact with said cylinder, a detergent solution in said receptacle about said absorbent member, and a squeegee device carried by said receptacle adapted to be pressed firmly against said cylinder for drying the cylinder after its contact with said absorbent member.

8. In a press, the combination of a trans-

fer cylinder, a plate cylinder adapted to revolve in contact therewith, means for applying water to the surface of lithographic plates carried by said plate cylinder, inking mechanism adapted to ink said plates, and means for cleaning the ink from said transfer cylinder, comprising a cylinder, a receptacle in which said cylinder is rotated, means for adjusting said receptacle relative to said cylinder, an absorbent member located in said receptacle and adapted to be brought into firm contact with said cylinder, a detergent solution in said receptacle about said absorbent member, a squeegee device carried by said receptacle for drying the cylinder after its contact with said absorbent member, and means for moving said squeegee device relative to said receptacle for pressing the said squeegee device firmly against the cylinder.

9. In a press, the combination of a transfer cylinder, a plate cylinder adapted to revolve in contact therewith, means for applying water to the surface of lithographic plates carried by said plate cylinder, inking mechanism adapted to ink said plates, and means for cleaning the ink from said transfer cylinder, comprising a cylinder, a receptacle in which said cylinder is rotated, means for adjusting said receptacle relative to said cylinder, an absorbent member located in said receptacle and adapted to be brought into firm contact with said cylinder, a detergent solution in said receptacle about said absorbent member, a squeegee device carried by said receptacle for drying the cylinder after its contact with said absorbent member, and a screw carried by said receptacle and bearing on said squeegee device for moving the said squeegee device firmly into contact with said cylinder.

JOSEPH L. FIRM.
